GARMENT HANGER

Charles Tyler, Redlands, Calif.

Application December 18, 1939, Serial No. 309,859

5 Claims. (Cl. 223—96)

This invention relates to garment hangers, and has for an object the provision of a garment hanger of such improved and simplified design that it is possessed of manifold advantages from the standpoint of the manufacturer and distributor as well as from that of the user.

A more detailed object of my invention is the provision of a garment hanger wherein the element upon which a garment supported thereby is engaged consists merely of a horizontal and preferably rigid bar supported solely from below, leaving its top and sides unobstructed so that a garment can be laid upon the bar with the ends of the garment hanging downwards therefrom upon opposite sides thereof, thus reducing to a minimum the amount of time and effort required to engage a garment upon the hanger.

Another object of my invention is the provision of a garment hanger capable of operation with the utmost facility in the manner indicated, and yet adapted to retain the garment or garments engaged thereupon with ample security against inadvertent dislodgment and in the best possible form for the retention of the garment's shape and press. Toward this end, a locking bar is provided, adapted to press the garment into firmer engagement upon the rigid bar and thus enhance the security of the garment's support by the device.

A further object in this connection is the provision of a locking bar as described of such design that its operation can be accomplished substantially instantaneously, and so arranged that it can be withdrawn from the rigid bar to such position that it does not interfere with the placing of garments thereupon, or their removal therefrom when desired.

Yet another object of the present invention is to provide a garment hanger of the character described which is capable of supporting a plurality of garments with equal facility and security.

Another object is the provision of a garment hanger possessed of the advantages referred to, and yet of such inexpensive construction that it is adapted for economical production and distribution and of such simple construction that it operates quickly and efficiently and with minimum liability of becoming out of order.

The invention possesses other objects and features of advantage, some of which, with those enumerated, will be set forth in the following description of the preferred embodiment of my invention illustrated in the drawing accompanying and forming a part of the specification. It is to be understood, however, that I do not limit myself to the showing made by the said drawing and description, as I may adopt variations of the preferred form within the scope of my invention as set forth in the claims.

Referring to the drawing:

Figure 1 is a view in front elevation of a gar-

ment hanger embodying the principles of the present invention.

Figure 2 is a side elevation, showing the manner of engagement of a pair of trousers thereupon. The position of the locking bar when withdrawn is indicated in broken lines; and parts of the figure are broken away and shown in section in order to reveal the construction.

Figure 3 is a detail view in section showing the manner of engagement of the bars upon their respective supporting frames. The plane of section is indicated by the line 3—3 of Figure 2, and the direction of view by the arrows.

In terms of broad inclusion, the garment hanger of the present invention comprises a base adapted to be mounted upon a suitable support and carrying a horizontal bar mounted upon the base by means which make connection with the bar only at its under surface, leaving the top and sides of the bar unobstructed, with the result that garments can be engaged thereupon merely by laying them across the bar with the ends of the garment hanging downwards therefrom on opposite sides. Disposed in parallelism and in cooperative relationship with this bar is a locking bar adapted to engage garments so laid across the first mentioned bar; and one of the two bars, preferably the latter, is movable toward and away from the other so that garments hung over the first mentioned bar in the manner described can optionally be securely fastened thereupon or released.

More specifically described, that embodiment of my garment hanger which is illustrated in the drawing comprises a base 6 adapted for hanging upon a vertical surface, such as a wall, door, or the like, toward which end it is provided with preferably a plurality of holes 7 and 8 for the reception of screws or the like. Adjacent the lower end of the base, a bracket 9 is provided for the support of a horizontal garment receiving bar 11; preferably the bracket 9 is in the form of a pair of spaced parallel legs 12 each of which extends from adjacent the side edge of the base 6. To impart greater rigidity to the bracket 9, each of these legs is provided with a vertical portion 13 extending upwards along the forward face of the base 6 for a material length and having at its upper end a short inwardly extending portion 14 seated within a complementary socket in the base 6 securely fastening the leg against displacement. Preferably these vertically extending portions 13 are concealed by a decorative post or cover strip 15. At the lower end of the vertically extending portions 13, each leg 12 has a forwardly extending portion 16 preferably substantially horizontal and at the forward end of this portion each leg extends substantially vertically upwards to the bar 11 as indicated at 17. It is apparent therefore that

the bar 11 is supported from underneath only, leaving its top and sides unobstructed. This is one of the important features of the present invention inasmuch as it affords the utmost convenience in placing garments upon the hanger.

The garment hanger is also provided with a locking or clamping bar 21 disposed parallel to and in co-operative relationship with the garment receiving bar 11 so as to aid in retaining garments thereupon. However, the clamping bar 21 is movable to and from its operative position, thereby permitting its withdrawal when it is desired to place garments upon the hanger and remove them therefrom. Toward this end the locking bar 21 is carried by frame 22 which also comprises a pair of spaced parallel legs 23 and 24 rigidly interconnected by a cross-bar 26. At their inner ends the legs 23 and 24 are deflected outwards to provide axially aligned pintles 27 journalled within suitable sockets in the inner faces of the cover strips 15. The locking bar 21 is carried upon the outer ends of these parallel legs 23 and 24. It is apparent therefore that the locking bar 21 is mounted for pivotal movement optionally to the full line position of Figure 2 wherein it is disposed adjacent to the garment receiving bar 11 or withdrawn therefrom upwards and inwards toward the base 6. A coil spring 28 is secured at one end of the base 6 as by a screw 29 and at the other end to the cross-bar 26. This spring 28, being under tension, serves to retain the pivotally mounted locking bar 21 in either of its two optional positions inasmuch as while swinging from one position to the other the frame 22 carries the spring 28 past its dead-center position; therefore, the locking bar 21 is resiliently and releasably retained either in its operating position or its withdrawn position, shown in full lines and broken lines respectively in Figure 2.

The locking bar 21 and its supporting frame 22 are so arranged with respect to the rigid garment receiving bar 11 that when the locking bar 21 is in operating position it overlies the rigid bar 11, but instead of being directly above it, is disposed slightly inwards toward the base 6 as clearly shown upon Figure 2.

As described hereinabove, the step of disposing a garment upon the hanger requires merely that the garment be laid over the rigid bar 11, thus permitting ends of the garment to hang downward upon opposite sides of the bar in much the same manner as one would lay a garment over the back of a chair. For example, Figure 2 illustrates a pair of trousers hung upon the hanger. Before placing the trousers upon the hanger, the operator has grasped the trousers by the cuffs and folded them at the creases, placing the two cuffs together with their respective front and after creases in contact with each other, then the operator has merely laid the legs of the trousers over the rigid bar 11 with the cuffs 31 hanging down from the bar 11 and between the bracket 9 and the base 6, the legs 32 of the trousers thus being permitted to hang down from the front of the bar 11. It has been found that inasmuch as a material length of the garment hangs down upon each side of the bar 11, a sufficient degree of friction between the bar and the garment develops to retain the garment against inadvertent displacement from the bar by sliding over it. This is explained by the fact that something of a "snubbing" action develops, and even though a considerably greater weight is imposed upon that portion of the gar-

ment which hangs down from the front of the bar, the weight of the cuffs 31 and that portion of the legs between the cuffs and the bar 11 is sufficient to develop the amount of friction with the bar which is necessary to prevent the garment from sliding. The manner in which the locking bar 21 is positioned, which has been described in detail hereinabove is significant inasmuch as it aids the locking bar in co-operating with the rigid bar to develop this "snubbing" action, as it presses the garment more firmly against the rigid bar and thus serves to increase the amount of friction therebetween. However, as a precautionary measure, the locking bar 21 is provided with a flat face 36 on that side thereof which is proximal to the supporting frame 22. As clearly shown in Figure 2, this flat face serves to present a relatively abrupt shoulder or edge along that portion of the locking bar with which the upper edges of the cuffs 31 would come in contact if the garment should start slipping over the rigid bar 11.

In some instances it may be desirable also to provide a leaf spring 37 secured as by screw 38 to the base 6 extending downwards and outwards to a position adjacent the inner face of the rigid bar 11. This spring presses upwards and outwards against the bar 11, but is relatively "soft" so that it can be pressed away from the bar easily to permit a garment to be thrust therebetween. The lower end of this spring 37 is preferably curled inwards as indicated at 39 so as to prevent its becoming caught in the fabric of any garments placed upon hanger. This spring tends to wrap the garments further around the rigid bar 11 and thus further enhance the snubbing action mentioned hereinabove.

The parts are so proportioned and arranged that the rigid bar 11 is disposed at a material distance from the base 6 and also above the horizontal portions 16 of its supporting bracket 9, the purpose being to permit the garment hanger to accommodate a plurality of garments. Particularly desirable is the space thus provided when the garment hanger is to be used to support a plurality of pairs of trousers having cuffs because of the increased thickness of such garments caused by the multiple layers of fabric necessary to provide the cuffs. However, it should be observed that so efficient is the snubbing action between garments and the rigid bar 11 over which they are hanging that even in the case of those garments not provided with cuffs, such as women's slacks, there is no tendency for the garments to be released and be permitted to fall from the hanger. Furthermore, the garments are held in the most desirable shape to preserve their form and press, particularly in the case of creased trousers or slacks because they are folded sharply at the creases and merely laid over a horizontal supporting bar which not only permits the garment to hang naturally, but also actually tends to sharpen the creases. However, the predominating feature of the device for the present invention is the fact that it can be operated with the utmost ease. Since the rigid bar 11 is entirely unobstructed, after the locking bar 21 has been moved to its withdrawn position all the operator has to do is to lay the garments over the rigid bar, a step which is so simple that it actually can be performed with one hand. The fingers of that hand should then press the cuffs down and between the rigid bar 11 and the leaf spring 37, whereupon the palm of the hand can be pressed against the garment where it

curves around the rigid bar 6 holding garment against falling off the bar while the fingers of the same hand reach up to engage the locking bar 21 and pull it downwards into engagement with the garment, securely anchoring the garment against dislodgment from the hanger. If it is desired to place a second garment upon the same hanger, the operation is repeated, the second garment merely being laid over the first already in position.

Another feature of importance that should be mentioned is the fact that both bars 11 and 21 are demountable from their respective supporting frames. The manner of their detachment from the frames is indicated in Figure 3, which illustrates the locking bar 21 and a portion of its frame 22, although it should be understood the manner of the engagement of the rigid bar 11 upon its bracket 9 is similar. At the extremities of the legs 23 and 24 of the frame 22 they are deflected outwards slightly in relatively sharp points 41. The holes 42 in the bar 21 into which the legs 23 and 24 are thrust are preferably slightly larger than the legs, thus permitting the ends of the legs 23 and 24 to be sprung together slightly as they are thrust into the holes 42. When the ends of the legs 23 and 24 reach the bottoms of the holes 42, the legs 23 and 24 should be permitted to spring outwards, whereupon the inherent resiliency of the material of which the legs are made will cause the points 41 to penetrate the material of the bar 21 and thus firmly anchor the bar upon the frame. The importance of this feature lies in the fact that it permits shipment and sale of the device in "knocked-down" form and assemblage by the purchaser with utmost facility and without requiring the use of any tools.

I claim:

1. A garment hanger of the character described, comprising a base adapted to be mounted in vertical position, a pair of spaced legs extending outwards therefrom for a predetermined distance and then extending upwards substantially in parallelism to said base, and a garment-receiving bar rigidly mounted upon the upper ends of said legs, said bar being materially longer than the spacing between said legs and both ends of the bar extending laterally beyond said legs, said rigid bar being horizontally disposed and having its top, sides, and ends unobstructed whereby a garment can be engaged thereupon by folding said garment around said bar with ends of the garment hanging downwards therefrom upon opposite sides thereof, said bar being spaced sufficiently from said base and from the outwardly extending portions of said legs to accommodate the cuffs of a plurality of garments within the spaced defined thereby.

2. A garment hanger of the character described, comprising a base adapted to be mounted in vertical position, a pair of spaced legs extending outwards therefrom for a predetermined distance and then extending upwards substantially in parallelism to said base, a garment-receiving bar rigidly mounted upon the upper ends of said legs, said rigid bar being horizontally disposed and having its top and sides unobstructed whereby a garment can be engaged thereupon by folding said garment around said bar with ends of the garment hanging downwards therefrom upon

opposite sides thereof, said bar being spaced sufficiently from said base and from the outwardly extending portions of said legs to accommodate the cuffs of a plurality of garments within the space thus defined, a locking bar adjustably mounted upon said base for movement optionally to garment-engaging position adjacent and parallel to said rigid bar or to withdrawn position spaced therefrom far enough to release garments thereupon, and spring means for releasably retaining said locking bar in either of its two said positions.

3. In a garment hanger of the character described, a horizontally disposed bar, supporting means rigid therewith and extending substantially vertically downwards therefrom at points spaced from the ends of the bar, whereby the top, sides and ends of the bar are left unobstructed and a garment can be engaged thereupon by folding said garment around the bar with the ends of the garment hanging downwards therefrom upon opposite sides thereof and said garment can be removed from the bar by sliding it while still folded longitudinally of the bar off an end thereof, and a locking bar movably mounted adjacent said first mentioned bar and movable theretoward in parallelism therewith to engage a garment upon said first mentioned bar.

4. A garment hanger of the character described, comprising a base adapted to be mounted in vertical position, a post affixed to said base adjacent each lateral edge thereof, a leg associated with each of said posts and comprising a vertical portion extending longitudinally of and concealed within the post, an inwardly extending portion at the upper end of said vertical portion fitted within a socket in said base, a portion extending outwardly from the lower end of the vertical portion to a position spaced materially in front of said base and an outer vertical portion extending upwards from the outer end of said outwardly extending portion, a garment-receiving bar rigidly mounted upon the upper ends of said outer vertical portions of said legs, said bar being horizontally disposed and having its top, sides and ends unobstructed whereby a garment can be engaged thereupon by folding said garment around said bar with the ends of the garment hanging downwards therefrom upon opposite sides thereof and said garment can be removed from said bar by sliding it while still folded longitudinally of the bar off an end thereof, and a locking bar disposed parallel to said first mentioned bar and movable theretoward to engage a garment upon said first mentioned bar.

5. A garment hanger comprising a base, supporting means extending rigidly therefrom, a garment-receiving bar rigidly mounted upon said supporting means, both ends of said bar extending laterally beyond said supporting means and the top, sides and ends of said bar being unobstructed whereby a garment can be engaged thereupon by draping the garment thereover with the ends of the garment hanging downwards upon opposite sides thereof, and can be removed therefrom by sliding the garment laterally off an end of said bar, and a leaf spring mounted on said base and pressing resiliently against said bar to engage a garment supported by the bar and releasably retaining it thereupon.

CHARLES TYLER.
